UNITED STATES PATENT OFFICE.

GEORGE HENRY PEDLAR, OF OSHAWA, ONTARIO, CANADA.

DESIGN FOR A METALLIC SHINGLE.

No. 39,890.

Specification for Design.

Patented March 23, 1909.

Application filed January 15, 1909. Serial No. 472,553. Term of patent 7 years.

To all whom it may concern:

Be it known that I, GEORGE HENRY PEDLAR, a subject of the King of Great Britain, residing at Oshawa, in the Province of Ontario, Canada, have invented a new, original, and ornamental Design for Metallic Shingles, of which the following is a specification, reference being had to the accompanying drawing, forming part thereof

The figure is a plan view of a metallic shingle, showing my new design.

I claim:

The ornamental design for a metallic shingle, as shown.

GEORGE HENRY PEDLAR.
